UNITED STATES PATENT OFFICE.

DANIEL B. HILL, OF GRAYVILLE, ILLINOIS.

MOTOR-PLOW.

1,019,252.

Specification of Letters Patent.

Patented Mar. 5, 1912.

Application filed May 9, 1910. Serial No. 560,194.

To all whom it may concern:

Be it known that I, DANIEL B. HILL, a citizen of the United States, and resident of Grayville, White county, Illinois, have invented certain new and useful Improvements in Motor-Plows, of which the following is a specification containing a full, clear, and exact description, reference being had to the accompanying drawings, forming a part hereof.

My invention relates to improvements in motor plows and is especially directed to that class of plows which are known as "gang" plows and are driven and steered by a motor carried by the frame thereof.

The primary object of my invention is to construct a frame, for carrying a number of plows, having cut away portions which permit of the turning of the whole structure in a minimum of space.

A further object of my invention is to construct a plow of this class in which the propelling and steering is accomplished by the employment of a motor carried by the plow frame.

For the above purposes my invention consists in certain novel features of construction and arrangements of parts as will be hereinafter more fully described, pointed out in the claims and illustrated by the accompanying drawings, in which:

Figure 1 is a plan of the plow, the operator's platform and cab being removed; Fig. 2 is an elevation of the complete plow; Fig. 3 is a transverse, vertical, sectional elevation taken approximately on the line 3—3 of Fig. 1; Fig. 4 is an enlarged, detail, sectional elevation taken on the line 4—4 of Fig. 1; Fig. 5 is a detail plan partly in section illustrating the means whereby the plow may be steered either by hand or by the motor; Fig. 6 is a vertical, sectional elevation taken on the line 8—8 of Fig. 5.

Referring by numerals to the accompanying drawings: 1 designates the frame proper which is substantially rhomboidal and at each of its side margins is provided with a semicircular portion 2, the semicircular portion, at the right hand side of the frame, being in advance of the left hand semicircle, and at the forward end of the frame there is an extension 3.

4 and 5 designate the supporting and driving wheels which are of any ordinary construction and each of which carries a bevel gear wheel 6. For connecting the

wheels 4 and 5 with the frame there are the bearing plates 7 which project laterally from the semicircular portions 2 and surmounting the bearing plates are the housings 8 arranged for the inclosing of the gear wheels 9, each of which is interiorly threaded for the engagement with and supporting of the threaded uprights 10. Connected with and preferably formed integral with the threaded uprights 10 are the bifurcated members 11 which embrace the bearing blocks 12 for the stub shafts 13 which support the wheels 4 and 5.

As shown, each of the housings 8 incloses a worm 14 normally in engagement with the gear wheels 9, and 15 designates cranks for the moving of said worms for the turning of the gear wheels 9 to raise and lower the frame over the threaded uprights 10.

For supporting the rear end of the frame there is a caster wheel 16 rotatably carried on a stem 17. Arranged at the apex of the frame at its rear end there is a housing 18, which housing is provided with integral wings 19 for attachment to the frame 1. The housing incloses a rectangular sleeve 20 having on its forward face teeth forming a rack 21 which sleeve embraces the stem 17 and is adjustably secured vertically relative to the stem by means of the collars 22. Arranged within the housing 18 is a gear wheel 23 mounted upon a shaft 24 which extends through the housing, and carried by a shaft within the housing and not shown is a gear 90 and worm connection with the shaft 24 manually operable by a crank 28. By this means the rearmost end of the frame may be raised or lowered as the forward end is raised or lowered over the threaded uprights 10, as required for different depths of plowing, but which means I did not claim in this application.

For driving the wheels 4 and 5 there is a motor 29 preferably a gasolene engine 100 which is carried by the extension 3 of the frame. The motor as shown is provided with a radiator 30 of ordinary construction, the connections between the motor and radiator being not shown. Carried by the frame 1 is a transmission gearing box 31 which is of ordinary construction and is connected with the engine shaft 32 in an ordinary manner. Extending from the transmission gearing box to a point adjacent the right hand side of the machine frame is a shaft 33 having on its end op-

posite the box a bevel gear wheel 34 which meshes with a gear wheel 35 carried on a shaft 36 arranged at right angles and beyond the shaft 33.

5 Extended vertically from the plates 7 are the bearing blocks 37 and intermediate the blocks 37 resting on the frame proper is a bearing block 38. Supported by these bearing blocks is a shaft 39 having at its 10 ends bevel gear wheels 40. Meshing with the wheels 40 are the bevel gear wheels 41 carried by the vertically disposed shafts 42 which are supported in bearings arranged in the ends of the bifurcated members 11 15 and at their upper ends are supported by bearings 43 formed integral with the bearing blocks 37. Each of the wheels 41 is feathered to a shaft 42. Carried by the shafts 42 are the bevel gear wheels 44, secured against rotation relative the shaft and arranged to mesh with the bevel gear wheels 6 carried by the guide wheels 4 and 5.

To impart motion to the shaft 39 there is a sprocket wheel 45 embracing the shaft 39 25 and a sprocket wheel 46 carried by the shaft 36 and these two sprocket wheels are connected by the chain 47. Thus, as the engine is operating, the motion therefrom, through the transmission gearing (not shown), rotates the shaft 33, which through the medium of the gear wheels 34 and 35, sprocket wheels 46 and 45 and chain 47 motion is imparted to the shaft 39. As the shaft 39 is rotated the driving wheels 4 and 5 are 30 driven through the medium of the bevel gear wheels 40, 41, 44 and 6. It is to be understood in this connection that the transmission gearing is provided with the usual means for reversing its movement as well as 35 to throw a clutch into or out of engagement with a locking member on the engine shaft as required and all of which is not shown for the reason that any common form of such means may be employed.

45 Two forms of steering devices are employed, one of which is operated solely by hand and the other arranged to be operated by the motor.

The means whereby the machine may be 50 steered manually comprises a post 48 which is arranged about centrally of the frame of the machine, at the top of which is fixed an ordinary hand wheel 49 and at or adjacent the bottom of the post is a worm 50 which is 55 keyed or otherwise secured to the shaft. The post is maintained in a vertical position by means of bearings 51 carried by a housing 52. Extended through the housing is a horizontal shaft 53 upon which is a worm 60 wheel 54 in mesh with the worm 50. Secured to the shaft 53 and extending downwardly at right angles to the shaft is a lever 55. Extending rearwardly from each of the shafts 42 beneath the bearing blocks 12 65 for the stub shafts 13 is an arm 56 which

arms are connected with a rod 57. Pivotally connecting the arm 56 with the lever 55 and actuated by the steering post is a connecting rod 58. By the means just described the two main driving and supporting wheels 70 are moved to steer the frame by a manipulation of the hand wheel 49.

For the steering of the caster wheel 16 simultaneously with the steering of the wheels 4 and 5 I have provided an arm 59 75 extended laterally from the stem 17, and carried by the frame of the machine is a bell-crank lever 60 and pivotally connected with one end of the lever 60 and with the arm 59 is a rod 61. The opposite end of the 80 bell-crank lever 60 is connected with the arm 56 by the rod 62. Thus, as the machine is steered, the various connecting devices operate the drive wheels in opposite directions relative the caster wheels. By reason of the bearings 37 and 38 the shaft 39 85 is supported in planes wholly above the drive wheels so that the drive wheels may operate beneath said shaft.

For connecting the steering apparatus so 90 that it may be operated by the motor I have provided a bevel gear wheel 63 on the transmission gear shaft 33. Supported on a shaft carried in bearings 64 pendant from the frame of the machine there is a shaft 95 65 which carries a bevel gear wheel 66 meshing with the gear wheel 63. Keyed or otherwise secured to the shaft 65 is a pair of connected friction disks 67. Supported in a bearing 68, which is arranged between the 100 friction disks 67, is a shaft 69 and keyed or otherwise secured to the shaft 69 is a friction disk 70 arranged for engagement with either one of the disks 67. The shaft 69 is extended through slots 71 formed in the 105 walls of the housing 52. Embracing the shaft within the housing is a worm 72 arranged for engagement with the worm 50^a carried by the steering post. The bearing 68 just referred to is clearly shown in Fig. 110 6 and is of the type which permits slight lateral play of the entire shaft 69.

For normally holding the worm 72 out of engagement with the worm 50^a of the steering post there is a collar 73 to which is connected a contractile coil spring 74.

For moving the shaft 69 to place the worm 72 in mesh with the worm 50^a of the steering post there is a bell-crank lever 75 carried by a bearing 76 projecting downwardly from the frame 1. One arm of the lever 75 is connected with the collar 73 by means of the link 77, and the other arm of the lever 75 is connected with a foot lever, not shown, by means of the link 79.

For varying the speed of the steering device the disk 70 may be moved toward or away from the centers of the disks 67 by means of the bell-crank lever 80, one end 125 of which is bifurcated and arranged to en-

gage a pin 81 carried by an integral part of the disk 70, the other end of the lever 80 is connected with a rod 82 which is connected with any suitable operating lever 5 (not shown).

For controlling the direction of the steering means the disks 67 are movable lengthwise relatively the shaft 65 so that they will engage at different times, opposite sides of 10 the periphery of the disk 70. For moving the disks 67 as above described there is a bell-crank lever 83, one end of which is bifurcated to straddle a pin 84 carried by an 15 integral part of the disks 67 and to the opposite end of the lever 83 is a rod 85 connected with a hand lever, not shown, provided with a pawl and segmental rack for holding the disks 67 in various set positions.

Located upon the frame of the machine 20 there is a platform 110 surmounted by a cab 111 for the occupancy of the operator of the machine and in which is located the various levers for controlling the various parts of the machine.

25 In the practical operation of the machine, assuming the motor to be in operation, it is obvious that the whole machine may be driven either forwardly or rearwardly according to the connection made between the 30 engine and transmission gearing shaft 33 by the transmission gearing not shown in detail. From the shaft 33 motion is imparted to the drive shaft 39 through the bevel gear wheels 34 and 35 and the sprocket 35 gearing 45, 46 and 47. From the shaft 39 motion is imparted to the drive wheels through the medium of the bevel gears 40, 41 and the bevel gears 44 which mesh with and rotate the bevel gears 6 carried by the 40 drive wheels. By reason of the location of the shaft 39 in a plane some considerable distance above the machine frame proper the wheels 4 and 5 may operate beneath said shaft as required in steering the machine.

45 As previously stated, the machine is normally in condition to be steered manually by means of the hand wheel 49 which is rigidly connected with the steering post 48. As the hand wheel is turned in either 50 direction, to the right or left, the wheels 4 and 5 and caster wheel 16 are turned through the medium of the levers 56 for the wheels 4 and 5 and lever 59 for the 55 caster wheel, which levers are connected by suitable rods with the steering post. By this arrangement the wheels 4 and 5 are simultaneously turned in the same direction while the caster wheel is turned in an opposite direction, thereby causing the entire 60 machine to be turned completely about in a minimum of space, as the wheels 4 and 5 operate in the cut away portions in the sides of the frame.

If, for any reason, the manual steering is 65 difficult or cannot be accomplished in the

required time the operator may connect the steering apparatus with the motor so that the steering may be accomplished by the motor. When the machine is steered by the motor the operator can direct the course of travel of the machine by the moving of the friction disks 67. By moving one of the disks to engage with a coöperating disk the machine is directed to travel to the right and by moving the said disk away from the 70 coöperating disk and placing the opposite disk 67 to engage with the coöperating disk the machine is directed to travel to the left. The speed of the steering device may be controlled by moving said coöperating disk toward or away from the centers of said disks 67.

By means of the threaded uprights 10 and the worms 14 the wheels 4 and 5 may be, if desired, vertically adjusted independently 85 of each other, as required for causing one wheel to ride over the land and another wheel to ride in a furrow or vice versa, or for leveling the entire machine to travel evenly over differential inclined lands. 90

I claim:

1. In a machine of the class described, a substantially rhomboidal frame, a substantially semicircular cut away portion in each side margin of the frame, one in advance of the other, a steering wheel, located for movements when steering, in each of said cut away portions, a wheeled support for the rear end of said frame, connections between all of said wheels whereby the first mentioned wheels may be turned in the same direction and the wheeled support for the rear of the frame turned in an opposite direction, manually operated means for steering all of said wheels, a motor, and means for connecting said motor with said manually operated steering means at times. 95

2. In a machine of the class described, a substantially rhomboidal frame, a substantially semicircular cut away portion in each side margin of the frame, one in advance of the other, a steering wheel, located for movements when steering in each of said cut away portions, a wheeled support for the rear end of said frame, connections between all of said wheels whereby the first mentioned wheels may be turned in the same direction and the wheeled support for the rear of the frame turned in an opposite direction, manually operated means for steering all of said wheels, a motor, means for connecting said motor with said manually operated steering means at times, and a manually operated means for changing the direction of movement of the steering apparatus when connected with said motor. 105

3. In a machine of the class described, a substantially rhomboidal frame having in each of the side frame members a semicircular portion, the semicircular portion in 110

one side of the frame being in advance of the other semicircular portion, bearing plates secured to the frame and projecting laterally in each semicircular portion, vertical shafts rotatably held in said bearing plates, driving wheels carried by said shafts, and means whereby the vertical shafts, supporting the driving wheels are simultaneously turned.

10 4. In a machine of the class described, a substantially rhomboidal frame in each side of which there is formed in the frame mem-

bers a semicircular portion, the semicircular portion in one side of the frame being in advance of the semicircular portion in 15 the opposite side of the frame.

In testimony whereof, I have signed my name to this specification, in presence of two subscribing witnesses.

DANIEL B. HILL.
